UNITED STATES PATENT OFFICE.

VINCENT SCATENA, OF PITTSBURGH, PENNSYLVANIA.

DESIGN FOR A SIGNAL-LIGHT CASING.

Application filed June 27, 1927. Serial No. 22,568. Term of patent 14 years.

To all whom it may concern:

Be it known that I, VINCENT SCATENA, a subject of the King of Italy, residing at Pittsburgh, in the county of Allegheny and State of Pennsylvania, have invented a new, original, and ornamental Design for Signal-Light Casing, of which the following is a specification, reference being made to the accompanying drawing, forming part hereof, in which

Figure 1 is a plan view of a signal light casing showing my new design;

Figure 2 is a bottom view of the signal light casing.

I claim:

The ornamental design for a signal light casing, as shown.

VINCENT SCATENA.
